UNITED STATES PATENT OFFICE

172,486

PLATE OR SIMILAR ARTICLE

A. Baker Barnhart, New York, N. Y., assignor to
The Rosenthal-Block China Corporation, New
York, N. Y.

Application March 30, 1953, Serial No. 24,264

Term of patent 7 years

(Cl. D44—15)

To all whom it may concern:

Be it known that I, A. Baker Barnhart, a citizen of the United States, residing in the city of New York, State of New York, have invented a new, original, and ornamental Design for a Plate or Similar Article, of which the following is a specification, reference being had to the accompanying drawing, forming a part hereof.

Fig. 1 is a top plan view of a plate or similar article of conventional configuration, showing my new design;

Fig. 2 is a partial, cross-section view taken along line 2—2 of Fig. 1.

I claim:

The ornamental design for a plate or similar article, as shown and described.
